VARIABLE FRACTION PLUG

Ralph R. Mondron and Romaine E. Mondron,
Mount Vernon, Ohio

Application April 29, 1947, Serial No. 744,642

7 Claims. (Cl. 33—80)

1

The present invention relates to improvements in glass cutting devices, and more particularly to variable fraction plugs, which are constructed and adaptable for use with the conventional glass cutting table and conventional cutting rule whereby the cutter may be enabled to shift the rule to fractional positions between the table pins in a manner which will facilitate the cutting of fractional sizes of window glass on a standard window glass cutting table.

An object of the invention is to provide a form of plug that will fit in window glass cutting tables with pins which are separated an inch apart, and which can be used with any of the conventional rules of window glass cutting tables.

Another object of the invention is to provide plugs adapted to interlock with the pins and having movable blocks with a calibrated arrangement enabling such blocks to move relatively to the plugs and to the pins to provide a vernier adjustment of positions between the pins, the blocks being constructed and arranged to receive the tip and hook of the cutting rule.

It is a further object of the invention to provide a variable fraction plug that will be capable of adjustment to various positions in a matter of seconds and that will enable a window glass cutter to make accurate cutting of all fractional sizes with the speed he will ordinarily cut regular sizes.

With the foregoing and other objects in view, the invention will be more fully described hereinafter and more particularly pointed out in the appended claims.

In the drawings, in which like parts are denoted by the same reference characters throughout the several views,

Figure 1 is a top plan view of the standard form of glass cutting table and rule with parts broken away and showing an adaptation of the improved variable fraction plugs as constructed in accordance with the present invention.

Figure 2 is a fragmentary perspective view of the far edge of the table showing the tip plug engaged with the vertically upstanding pins.

Figure 3 is a similar view of the near edge of the table with one of the hook plugs shown engaged with the horizontally projecting table pins, and

Figure 4 is a section taken on the line 4—4 in Figure 1.

Referring more particularly to the drawings, 10 designates a standard form of glass cutting table having at the far edge thereof from the cutter a row 11 of vertical pins which are spaced from another the distance of one inch, and 12

represents a second row of pins at the near side of the table which project out horizontally from the table edge in the well known manner and are conventionally spaced from one another the distance of one inch.

The invention is useful with the standard form of cutting rule 13 having the usual tip 14 at its far end and the hook 15 laterally of its handle end.

10 According to customary practice the tip 14 of the rule 13 is adapted to engage between pins 11 which gives the 1" adjustment to the rule 13 from pin to pin. In a similar manner the hook 15 cooperates in a like manner with the horizontal pins 12 to hook over an appropriate pin and gives the same 1" adjustment.

However, the standard table does not offer any fractional adjustments for the rule 13 between the 1" pin positions and it is the purpose of the present invention to provide such an arrangement.

We accordingly provide one or more sets of variable fraction plugs, two blocks constituting a set. Figure 2 shows one of the plugs which for convenience we might call the tip plug as it cooperates with the tip 14 of the standard rule 13. This plug is arranged at the far edge of the table and cooperates with the upstanding vertical pins 11.

20 The other plug of the pair is shown in Figure 3 and might be conveniently termed the hook plug inasmuch as it cooperates with the hook 15 of the standard rule 13 and is adapted to be engaged with the horizontal pins 12 at the near edge of the table.

30 Referring more particularly to Figure 2, the tip plug comprises a base block 16 having vertical holes 17 therethrough to enable the base block 16 to be dropped over a pair or more of the upstanding pins 11. Thus the base block 16 may be set at any position along the row of pins 11. A set screw 18 mounted in the back of the base block 16 opposite one of the holes 17 may bind upon a pin 11 to hold the plug in the adjusted position.

40 The base block 16 carries a slide block 19 slidable upon a bolt or pin 20. A set screw 21 carried by the slide block 19 is arranged to bind against the bolt 20 to maintain the slide block 19 in adjusted position relatively to the base block 16. A V or other notch 22 in the inner edge of the slide block 19 is adapted to receive the tip 14 of the cutting rule 13.

50 The slide block 19 is mounted in the cut-away portion 23 formed at the inner longitudinal edge

of the base block 16 thus producing inwardly projecting lugs 24 and 25 on the base block 16 in which the ends of the bolt 20 may be mounted whereby the bolt may be spaced inwardly from the longitudinal edge of the cut-away portion 23.

The slide block 19 is inscribed with an index mark 26 movable over a fraction scale 27 inscribed on the upper edge of the base block 16 near the adjacent edge of the slide block 19 which bears the index 26.

Referring more particularly to Figure 3, the other variable fraction plug comprises a base block 28 having holes 29 horizontally through portions thereof originating at the inner end of the block and adapted to receive a pair or more of the horizontal pins 12 at the near side of the table. A set screw 30 mounted through a side of the block is adapted to engage one of the pins 12 in order to bind the block in the adjusted position; it being understood that the base block 28 may be moved along the near edge of the table to any desired position and engage with any adjacent pair of the pins 12 where it is affixed by the set screw 30.

A slide block 31 is horizontally movable relatively to the base block 28 in a cut-away portion 32 formed in the outer edge portion of the base block 28 and resulting in the formation of the outwardly projecting lugs 33 and 34. A bolt or pin 35 is mounted in the lugs 33 and 34 and the slide block 31 is perforated to slide upon this bolt 35. A set screw 36 threaded into the slide block 31 is arranged to bind against the bolt 35 to hold the slide block 31 in adjusted position. A cylinder block 37 which may also be conveniently carried by the set screw 36 is rotatably or otherwise mounted outwardly of the slide block 31 so as to move back and forth therewith.

Vertical slots 38 and 39 are made through the base block 28 in alignment with the row of pins 12. The slot 38 is so related to the holes 29 that it extends between pins 12 and the holes 29 engage adjacent pins and this central slot 38 is bounded on all horizontal sides by portions of the base block 28 inasmuch as it is made substantially centrally of the block 28. On the other hand the vertical slot 39 occurs at one of the holes 29 and a pin 12 is adapted to extend across this slot 39 when the plug is mounted upon the table. Also the slot 39 is open through one edge of the base block 28. The hook 15 of the standard cutting rule 13 may be engaged in one or other slot 38 or 39 when such hook 15 is in alignment with the pins 12; or when the hook 15 is projected further back toward the operator the cylinder block 37 is positioned to receive this hook 15.

An index marking 40 is inscribed upon the top inner edge of the slide block 31 in a position to move over a fraction scale 41 inscribed upon the adjacent upper edge of the base block 28.

In the use of the device the plugs will probably be made of hard metal and be fitted to the table in pairs as indicated generally in Figure 1. The slide block 19 of the far plug is designed to fit the tip 14 of the cutting rule 13. The slide block 19 will slide along the bolt 20 to the desired fraction indicated by the index 26 moving over the scale 27. This movement may be accomplished by first backing off the set-screw 21, shifting the slide block 19 to the new position which may be quickly achieved by the aid of the index marking 26 and scale 27 and the utmost accuracy is provided by this arrangement. The set screw is thereupon fastened in the new position and the tip 14 of the rule 13 has been brought to a position between

adjacent pins 11. The slide block 19 and scale arrangement enable the tip 14 of the rule 13 to be brought to a great many fractional positions which the standard table does not provide.

5 The companion plug 28 at the near side of the table will be fitted to the pins 12 and secured thereby by the set screw 30 in a position which may be slightly offset from the bar plug 16 inasmuch as it will be desirable in most instances to 10 have the cylinder block 37 in position to be engaged by the hook 45 of the rule 13 and this hook is offset to the right of the rule in accordance with the standard construction. The cylinder block 37 will be offset away from the line of the pins 12 by substantially the same distance that the tip 14 is offset from its vertical line of pins 11 by the fact that it is engaging the slide block 19 of the far plug. This cylinder block 37 with the slide 15 31 can be adjusted to any fractional intermediate position between adjacent pins 12 in a manner similar and corresponding to the adjustment made of the far plug. Thus the hook 15 of the rule 13 may be accommodated by the cylinder block 37 in the position in which the straight edge 20 of the rule 13 will be truly transverse of the table to guide the cutting implement in the proper fractional cut.

The near plug can also catch the hook 15 in either of the slots 38 and 39 when a regular size 30 falls on the same fractional sides (such as 20 x 20 1/4) without removing the plugs. When such a size occurs the rule 13 will slip over the far plug 16 with its tip 14 engaging between the pins 11 and thus the hook 15 on the handle end of the rule 35 13 will move inwardly of the table to its normal position in line with the pins 12. In such position the rule hook 15 may engage in either slot 38 or 39 of the near plug 28.

Approximately six pairs of these fraction plugs 40 will constitute the set that will enable a cutter to cut any fractional size up to 1/32 of an inch. Such plugs are not complicated and are easy to set up and will not have to be removed until the cutting of the fractional sizes is completed.

45 It will be appreciated that the invention is very beneficial to the window glass trade as more and more fractions seem to be entering the every day routine.

It will also be appreciated that with the use of 50 the improved plugs a window glass cutter is enabled to cut fractional sizes with substantially the same ease as he cuts regular sizes on the standard window glass cutting table.

It will also be appreciated by those skilled in 55 the art that the improved plugs are efficient and accurate and will save a window glass cutter up to 50% of loss of time over previous methods. The plugs will promote speed and efficiency in the cutting of glass, particularly for cutting multiple 60 lights of the same fractional size out of a sheet of window glass; for example 8 1/16 x 12 out of a sheet of glass 45 x 85 would bring 35 lights of that fractional size or approximately one-half box.

While we have disclosed herein the best form of 65 the invention known to us at the present time we desire it to be understood that we reserve the right to make changes and modifications in the herein described embodiment of the invention provided such changes fall within the scope of 70 the following claims.

What is claimed is:

1. For use with a standard glass cutting table having spaced pins at opposite edges thereof and a standard cutting rule having a tip at its far end and a hook near its handle end, a variable

5

fraction plug device comprising a pair of plugs including a tip plug and a hook plug, said plugs adapted to engage the tip and hook respectively of the cutting rule, said plugs each having slide blocks constructed and arranged to receive the tip and hook respectively of the rule and slidably mounted in their respective plugs, a fraction scale and index between the plugs and their respective slide blocks for indicating fractional positions of the slide blocks between the pins, and means for holding the slide blocks in adjusted position.

2. A variable fraction plug device as claimed in claim 1 characterized by the fact that the tip plug has substantially vertical holes for receiving adjacent vertical pins of the table, and means to bind the plug upon the table.

3. A variable fraction plug device as claimed in claim 1 wherein a cut-away portion of each plug receives a slide block and such cut-away portion provides lugs projecting from the plug and carrying a bolt on which the slide block slides in the cut-away portion.

4. A variable fraction plug device as claimed in claim 1 in which a bolt mounted in each plug provides the means on which the slide block is slidably mounted and a set screw through the slide block engages the bolt to hold the slide block in adjusted fractional position.

5. A variable fraction plug device as claimed in

6

claim 1 characterized by the fact that the hook plug is provided with vertical slots therein in substantial alignment with the pins at the hook side of the table to receive the hook of the rule when the tip is slid over the tip plug to engage the tip pins on the table.

6. A variable fraction plug device as claimed in claim 5 in which one of the vertical slots is in the central portion of the hook plug and between adjacent holes for the pins, while another vertical slot is in alignment with a hole for the pin and is exposed through an end wall of the hook plug.

7. A variable fraction plug as claimed in claim 1 in which the slide block of the hook plug has a set screw for binding the same in adjusted position with a cylinder block rotatably carried by said set screw in position to be engaged by the hook of the rule.
